[57] CLAIM

The ornamental design for a child security gate, as shown and described.

DESCRIPTION

FIG. 1 is a front perspective view of a child's security-gate embodying our new design with broken lines suggesting the manner in which the gate is mounted in a doorway;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof; and,

FIG. 7 is a left side view thereof.
